UNITED STATES PATENT OFFICE.

LONNIE THOMAS PENNY, OF RALEIGH, NORTH CAROLINA.

CAR-DOOR LOCK.

Application filed November 15, 1924. Serial No. 750,133.

To all whom it may concern:

Be it known that I, LONNIE T. PENNY, a resident of Raleigh, in the county of Wake and State of North Carolina, a citizen of the 5 United States, have invented certain new and useful Improvements in Car-Door Locks, of which the following is a specification.

My invention relates to improvements in 10 car door locks, and refers particularly to a lock for use on the sliding doors of freight cars, although the lock may be used for any purpose or in any situation where it will operate in a practical and useful manner.

One object of my invention is the provision of a lock which can be easily placed 15 upon cars in common use, or upon new cars at the time of manufacture and at a price very much lower or cheaper than the locks 20 in general use, while overcoming the objections and defects in the locks in common use.

Another object of my invention is the provision of a sliding door lock which will 25 upon the closing of the door lock automatically and which can be easily opened and closed with the expenditure of very little effort, enabling a single attendant to lock and unlock the door.

Another object of my invention is a provision of a lock for sliding doors which will permit of the easy opening of the door and the locking thereof to provide a small space, 30 for the purpose of ventilation where such 35 is frequently required under present conditions.

Another object of my invention is a provision of a lock for sliding doors which will assist in the entire opening and closing 40 of the door, or of the partial opening of the door, and which will provide an absolutely reliable securing means for the door under all conditions, and which can only be unlocked by the proper person.

Another object of my invention is a provision of a lock for sliding doors which will be of the simplest, cheapest and most durable construction, which will withstand 45 the hardest usage without danger of getting 50 out of order, and which in every particular will be thoroughly efficient and practical.

To attain the desired objects my invention consists of a lock for sliding doors embodying novel features of construction 55 and combination of parts, substantially as

described and distinguished by the claims, and as shown in the accompanying drawings, in which:

Figure 1 represents a side elevation of a portion of a freight car with my lock shown 60 applied and in locked position and also showing in dotted lines the positions the parts occupy when the door is locked in slightly open position.

Fig. 2 represents a front elevation on an 65 enlarged scale of the lock to show its details of construction.

Fig. 3 represents an end elevation of the lock taken from one side, with the hasp or locking bar in locked position and in section. 70

Fig. 4 represents an end elevation taken from the opposite side of the lock, and

Fig. 5 represents a top plan view of the lock with the parts in locked position.

Referring by numeral to the drawings in 75 which the same numbers of reference are used to denote like parts in all the views:

The numeral 1 designates a portion of a freight car, 2 the sliding door thereof, 3 the guide rail and 4 the rollers carried by 80 the door and travelling on said guide rail, while the door may be provided with a suitable grasping portion or handle 5, to permit ready sliding of the door back and forth.

Secured upon the door near one edge and 85 in horizontal position by means of suitable fastening 6, is the strap or plate 7, which forms an anchoring means or support which is formed with a lug or raised portion 8, upon which by means of the nut or pin 9, is pivoted the bent end 10, of the hasp or locking lever 11, said lever being provided with a series of keepers 12 and a manipulating handle 13.

Secured to the car and near the edge of its 90 opening is the vertical plate 14, rigidly retained by fastenings 15 and having at its lower portion the angle arm 16, provided with an outstanding ear 17, adapted as will presently appear to form a fulcrum for the hasp or locking lever, while extending from said plate is the flange 18, provided with the hasp guiding portion 19, and the recess 19', to form the keeper for the hasp, while pivoted to said flange at its upper end 20, is the 100 arm 21, formed with the hasp engaging notch 22, and having near its lower portion an opening 23 in register with an opening 24 on the flange 18, to receive a seal or lock, not shown, and said pivoted locking arm is 110

further provided with a stop 25, to limit the movement of said arm inwardly with reference to the flange 18.

From the foregoing description taken in connection with the drawings the extreme simplicity and the operation of my lock will be readily understood, and it will be noted that when the door is slid to closed position the locking lever will automatically move the locking arm out of its path and assume the position shown in Figures 3 and 4 and that the locking arm will swing into locked position and that when desired to open the door for a limited distance the locking lever will bear against the lug on the plate after the manner of a fulcrum forcing the door for a short distance, when the locking lever will engage the locking bar and the parts will assume the position shown in dotted lines in Fig. 1.

The advantages of my lock will be readily understood by all persons skilled in such matters and it will at once be apparent that cars can be equipped with my lock at no greater cost than the defective locks in common use and will provide a lock which will prove useful, efficient, and thoroughly practical.

It will be noted that the first of the series 30 of keepers 12 is formed with a slight offset or rounding portion which enables it to slide more readily into locking engagement and it will also be noticed that the lever 7 can be used to open the door by its engagement 35 with the ear 17, this ear forming a fulcrum and permitting easy opening of the door by the single attendant.

All things considered the car door lock 40 being capable of production at a much less price than the locks in common use; being easily applied to old or new cars; being entirely automatic in operation and providing a reliable lock; and also acting as a booster to open the door insures the improvement 45 filling a long felt want in a perfect manner.

I claim:

1. In a lock for sliding doors, the combination with the car and door, an anchoring plate secured to the door, a plate rigidly secured to the car in proper relation to said anchoring plate, a locking lever pivoted to the anchoring plate, locking means carried by the plate secured to the door for securing the locking lever in locked position consisting of a keeper carried by said plate, a pivoted arm carried by the plate and coacting with said keeper, and means for sealing and securing said locking means and lever. 55

2. In a lock for sliding doors, the combination with the car and door, a plate secured to said door, a pivoted locking lever having a series of keepers, a plate secured to the car and having a recess to receive said keepers, a pivoted arm carried by said plate and adapted to engage said locking lever to retain it in secured position, and adapted to receive a permanent lock for securing the arm and locking lever said lock passing through the plate and pivoted locking arm. 60 65

3. A lock for sliding doors, consisting of an anchoring plate, a locking lever pivoted to said plate, a plate formed with a locking recess to receive said locking lever, a fulcrum formed on said plate and consisting of an inward extending arm having an ear to be engaged by said locking lever, and an arm for retaining said locking lever in locked position. 70 75

4. In a car door lock the combination with the car and door, a pivoted locking lever secured to the door, a plate secured to the car, a keeper on said plate to be engaged by the locking lever, a pivoted arm on said plate to coact with said keeper to retain the locking lever, the keeper and arm having openings to receive a lock, and a raised portion on said plate to form a fulcrum for the locking lever to force the car door open. 80 85

In testimony whereof I hereunto affix my 90 signature.

LONNIE THOMAS PENNY.
